UNITED STATES PATENT OFFICE.

CHARLES F. ROOT, OF RAVENNA, OHIO.

SAFETY DEVICE FOR STAYING-MACHINES OR THE LIKE.

1,286,419.

Specification of Letters Patent.

Patented Dec. 3, 1918.

Application filed August 12, 1916. Serial No. 114,519.

To all whom it may concern:

Be it known that I, CHARLES F. Root, a citizen of the United States, and resident of Ravenna, in the county of Portage and State of Ohio, have invented certain new and useful Improvements in Safety Devices for Staying-Machines or the like, of which the following is a specification.

In my prior Patent, No. 1,131,161, of March 9, 1915, there is disclosed a safety device for use on punching machines, box-staying machines, and similar machines, involving the use of a reciprocating work-performing element, the purpose of the safety device being to render the actuating means inoperative if the work-performing element contacts during its operative stroke with the operator's fingers, or any other obstruction extraneous to the work. The safety mechanism disclosed in the aforesaid patent is illustrated in a punching machine and is incorporated in a pitman or link interposed between the actuating eccentric and the punch and comprises a pair of gags carried by pivoted arms which are automatically shifted just before the punch reaches the work to move the gags to their operative position between two normally telescopic parts of the pitman. A spring and gravity is depended upon to restore the arms and the gags carried thereby to their inoperative position after the punch operates upon the work, but if for any reason these means should fail to operate, the gags would not be restored to their inoperative position and the pitman would then not operate as a safety device.

It is the object of the present invention to provide means for positively restoring the gags to their inoperative position, and this is preferably effected by means of a cam which, in the event of failure of the above-mentioned non-positively acting means to return the gag-arms to inoperative position, will positively act upon said arms and shift them back to inoperative position.

The invention is illustrated in the accompanying drawings, in which:—

Figure 1 is a front elevation of a portion 50 of a box-staying machine involving the use of a safety device constructed as above described;

Fig. 2 is a side elevation of the construction shown in Fig. 1;

Fig. 3 is a front elevation of the safety link or pitman with certain of the parts partly broken away;

Fig. 4 is a vertical section taken on the line 4—4 of Fig. 5; and

Fig. 5 is an enlarged side elevation of the safety link or pitman and the mechanism for actuating the gag-arms.

The above-mentioned safety link or pitman comprises a part 1 telescopically receiving the shank 4 of the other part 2 in a passage 3 provided for said shank. The shank 4 has a longitudinal slot 5 in its upper portion, through which a transverse pin 5' passes. This pin 5' by engagement with the end wall 6 formed by the slot 5, limits the downward movement of the part 2. The upward movement of the shank 4 is restricted by the length of the slot 5.

The shaft A of the machine, which is conventionally illustrated in the drawings, has an eccentric B which, connecting with the head of the part 1, effects a reciprocatory movement of the link, and in order to prevent the up and down movement of the link from throwing or moving the part 2 upwardly relative to the part 1, seats 7 are provided on the shank 4 which receive therein balls 9, the latter projecting and having movement in transverse apertures 8 provided in part 2. Plungers 10 also are disposed in the apertures 8 and slide therein, being normally tensioned by springs 11 which are carried by part 1 and which exert sufficient pressure on the balls 9 to hold the same in their seats.

A pair of opposed curved arms 13 and 14 are pivoted, by means of pins 15 and 26 respectively, to the part 2 in such manner that gag blocks 17 and 18 carried by the upper ends of the arms 13 and 14 respectively, will normally move outwardly and occupy the inoperative or open position shown in Fig. 1. Lugs 19 and 20 respectively, depend from arms 13 and 14 and are connected by means of a coil spring 21, the latter acting to pull upon the arms 13 and 14 so as to maintain the same in the outward position shown in Fig. 1; stops 35 and 36 respectively, being borne by the arms 13 and 14 to

engage the head of part 2 so as to limit the outward movement of said arms.

A pair of arms 22 and 23 are pivoted upon part 1 by screws or the like, 24 and 25, respectively and have interengaging male and female parts 26' and 27, in order to effect simultaneous movement of said arms 22 and 23, the latter having lateral stop members 28 and 29, respectively which engage with intermediate portions of the arms 13 and 14 as depicted in the drawings. The arm 23 is provided with an extension 30 which is adapted to contact with the lever 31 pivoted to the machine. A head H carrying the die or other tool P, is fastened to the part 2 of the link in any suitable manner, as by means of a pintle 40 on the rear face of the head H, which engages an eye 41 in the lower end of part 2 of the link.

In operation, the lever 31, which is arranged to project into the path of travel of the extension 30 of the arm 23, contacts with said extension just prior to the instant that the punch P engages with the work that is placed on the anvil N. The extension 30, upon contacting with the lever 31, will be rocked upwardly and thereby cause the stops 28 and 29 of arms 22 and 23 to move inwardly toward each other, thus causing said stops to actuate the arms 13 and 14 so as to move the gag-blocks 17 and 18 borne by the arms 13 and 14, inwardly toward each other so as to interpose the blocks 17 and 18 between the end 32 of part 1 and the shoulder 33 of the part 2, with the result that the downward movement of the part 1 will be communicated to the part 2 and thereby to head H and die P through the intermediary of the interposed blocks 17 and 18. Should, however, any obstruction occur between the anvil and punch, such as the finger or hand of the operator, the punch will contact with such obstruction before the extension 30 can reach or touch arm 31, consequently, the slight tension which the springs 11 exert on the balls 9 will be overcome, and the part 1 will continue its downward movement independently of the part 2, this being due to the fact that the extension 30 has not engaged the lever 31 to shift the arms 13 and 14 from the position shown in Fig. 1, in which position the blocks 17 and 18 are not interposed between parts 1 and 2, and which interposition of said blocks is necessary if part 2 is to partake of the working stroke of the part 1.

After the punch operates upon the work, the spring 21 restores the arms 13 and 14 and the gag-blocks 17 and 18 to their inoperative position.

The construction so far described is substantially the same as that shown in my aforesaid patent. It will now be noted that if the arms 13 and 14 are not restored to

their inoperative position, either by gravity, or by the action of the spring 21 as in case of breakage of the latter, the parts of the link could not telescope upon meeting an obstruction on the succeeding down stroke of the punch, and hence the safety feature of the device would be destroyed. This objection is overcome by providing means in addition to the spring 21 for positively acting upon the arms 13 and 14 to return them to inoperative position. This means preferably comprises a cam a which is pivoted at 37 to the bracket 38 which carries the lever 31. The bracket 38 is in turn connected to a second bracket 39 which is vertically adjustable on the machine to vary the time at which the lever 31 acts upon the projection 30 during the down stroke of the work-performing element. A spring 42 connecting the extremity of the lever 31 with the lower end of the bracket 39 yieldingly retains the lever 31 in the position shown in the drawing, but permits it to be rocked about its pivotal connection 43 when the projection 30 contacts therewith.

The cam a, as best shown in Fig. 4, has two lateral edge portions b and c which are bent approximately at right angles to the plane of the cam. The bent edge portion b is continued upwardly to form an arm b' and the bent edge portion c is continued upwardly to form an arm c'. The arms b' and c' are substantially parallel and normally lie between two pins d and e carried by the arms 13 and 14 respectively. The lower edge portions b and c are inclined toward each other. The arms b' and c' prevent inward movement of the arms 13 and 14 until the projection 30 contacts with the lever 31, at which time the pins d and e will be adjacent the inclined portions b and c, and hence will be free to move inwardly. The cam, therefore, does not interfere with the automatic throwing in of the gag-blocks, as above described. On the up-stroke of the link, if the spring 21 fails to restore the arms 13 and 14 to their inoperative position, the inclined cam-like portions b and c will act upon the pins d and e to move them outwardly, and hence shift the arms 13 and 14 to the inoperative position. The arms b' and c' extend upwardly a sufficient distance to hold the arms 13 and 14 in their outward position during the remaining part of the up-stroke of the link or pitman.

The pivotal mounting of the cam at 37 permits the cam to rock slightly to accommodate itself to the constantly changing inclination of the pitman.

The cam a is adjustable in a vertical direction with the lever 31, as they are both carried by the bracket 38 which is in turn carried by the vertically adjustable bracket 39.

Obviously the exact mounting of the cam and the specific shape thereof are immaterial to the invention, as the invention contemplates any means in combination with a safety device of the type shown for positively restoring the gag-arms to their inoperative position.

What I claim is:—

1. In a machine of the kind described, the combination with the work-performing element and its actuating means, of a pair of telescopic parts interposed between the same, a pair of gag-arms pivoted to one of said parts having gag-blocks adapted to be interposed between said telescopic parts to render them rigid and non-yieldable, automatic means to shift said arms to their operative position just prior to the engagement of the work by the work-performing element to render said parts non-yieldable, and a cam carried by a stationary part of the machine and being positioned and operative to automatically act upon both of said arms to positively restore them to their inoperative position.

2. In a machine of the kind described, the combination with the work-performing element and its actuating means, of a pair of telescopic parts interposed between the same, a pair of gag-arms pivoted to one of said parts having gag-blocks adapted to be interposed between said telescopic parts to render them rigid and non-yieldable, automatic means to shift said arms to their operative position just prior to the engagement of the work by the work performing element to render said parts non-yieldable, and a cam pivotally associated with a stationary part of the machine and adapted to automatically act upon both of said arms to positively restore them to their inoperative position.

3. In a machine of the kind described, the combination with the work-performing element and its actuating means, of a pair of 45 telescopic parts interposed between the same, a pair of gag-arms pivoted to one of said parts having gag-blocks adapted to be interposed between said telescopic parts to render them rigid and non-yieldable, automatic means to shift said arms to their operative position just prior to the engagement of the work by the work-performing element to render said parts non-yieldable, a projection associated with each of said arms, and 55 a cam pivotally associated with a stationary part of the machine between said projections and adapted to simultaneously act upon both of said projections to restore said arms to their inoperative position. 60

4. In a machine of the kind described, the combination with the work-performing element and its actuating means, of a pair of telescopic parts interposed between the same, a pair of gag-arms pivoted to one of said 65 parts having gag-blocks adapted to be interposed between said telescopic parts to render them rigid and non-yieldable, a vertically adjustable bracket carried by the machine, means supported by said bracket for shifting said arms to their operative position just prior to the engagement of the work by the work-performing element to render said parts non-yieldable, and a cam also supported by said bracket positioned and 70 operative for automatically restoring both said arms to their inoperative position. 75

Signed at Mansfield, in the county of Roland and State of Ohio, this 8 day of August, A. D. 1916.
